OWNER'S ROOM.

No. 11,241.

June 10, 1879.

RICHARD SMITH'S

NEW DESIGN FOR STRAIGHT AND ELLIPTICAL INTERCHANGEABLE COMBINATION FLOURISHES FOR ORNAMENTING PRINTING TYPES.# UNITED STATES PATENT OFFICE.

RICHARD SMITH, OF PHILADELPHIA, PENNSYLVANIA, ASSIGNOR TO MACKELLAR, SMITHS & JORDAN, OF SAME PLACE.

DESIGN FOR A FONT OF PRINTING-TYPES.

Specification forming part of Letters Patent No. 11,241, dated June 10, 1879; application filed May 3, 1879.
[Term of patent 14 years.]

To all whom it may concern:-

Be it known that I, RICHARD SMITH, (assignor to MACKELLAR, SMITHS & JORDAN,) of the city and county of Philadelphia, Pennsylvania, have invented and produced a new and original Design for a Font of Printing-Types, of which the following is a specification.

The nature of my design is clearly shown in the accompanying typographic impressions, to which reference is made. It consists of a design for a font of printing-types, to be used principally in the formation of borders and ornamental surroundings for printed matter.

No. 3 is a figure composed of a dot followed by a curved line, terminating in a scroll upon the right.

No. 4. The reverse of No. 3.

No. 1. A dot followed by a vertical line, crossed about centrally by a horizontal line proceeding from a dot upon the left. Below the horizontal line, upon the right of the vertical line, a square is formed.

No. 2. The center of the figure is composed of a ring, from which proceed the eight rays, as shown.

No. 5. A shaded spear-head-like figure, followed by a dot.

No. 9. A small dot followed by a larger dot, and this by a ring followed by a rhomboidal figure; this followed by a ring, a dot, and a smaller dot.

No. 10. The base of the figure consists of a horizontal line from which proceeds upward upon the left a curved line terminating in a dot, and upon the right an inclined line, upon the left of which is formed the oblong figure, the lower line of which extends beyond the incline line to the right and terminates in a dot.

No. 11. The reverse of No. 10.

No. 6. A ring placed centrally between two parallel lines having curved terminations. These parallel lines are broken and form the semicircles in the center.

No. 7. A scroll terminating in a ring upon the left. From the center of the same proceeds the bifid figure, followed by a ring.

No. 8. The reverse of No. 7.

No. 15. A figure composed of a trapezoidal figure terminated on the left in a dot; this followed by a bifid figure; this succeeded by two joined curled leaves; to the right of the leaves a rhomboidal figure shaded by vertical lines and ornamented by two tendril-like projections, the right angle being extended to the right in a horizontal line and terminated by a ring.

No. 14. The central portion of the figure consists of a horizontal line, upon the right of which is a dot, and upon the left a dot followed by a spear-head-like ornament. This line upon the right for the greater portion of its length is inclined between two parallel lines terminating upon the left in the curves followed by the dots, and upon the right extended so as to form very nearly a rhomboid.

No. 12. Commencing upon the right of this figure is a dot followed by a ring, and this followed by a horizontal line terminating upon the left in a curved line terminating in a dot. From this curved line proceeds upon the right a line inclined downward and terminating in the curve followed by a dot.

No. 13. The reverse of No. 12.

No. 23. A horizontal line having upon the left the tendril-like ornament, and upon the right a scroll terminating to the right in a dot.

No. 24. The reverse of No. 23.

No. 18. The center of the figure is a dot. Above this is a V-shaped figure, apex downward. Above the hollow space extends a small triangle, base downward. About the two lower sides of the V-shaped figure and the dot are curved lines parallel to them. On the left the curved line is angularly deflected downward and to the left, then downward and to the right, terminating in a scroll upon the left. On the right the curved line is angularly deflected downward and to the right, then downward and to the left, terminating in a scroll upon the right. Below the center of the figure formed of the dot and ring are two short parallel curved lines.

No. 16. Upon the right a scroll having the tendril-like ornaments, and terminating upon the left in a ring, as shown. From this ring proceeds upward a curved line, connected by an inclined line to a curved line with dot termination.

No. 17. The reverse of No. 16.

No. 26. This figure consists of a semi-anthemion placed horizontally, the central bud terminating in a tendril and slender line at the left; on the right in a scroll, which rounds to the left and over the semi-anthemion, and terminates in a tendril. Below the lower right scroll is a small tendril.

No. 27 is the reverse of No. 26.

No. 32. The center of the figure is a dot or ring, from which extend eight rays, the two vertical and the two horizontal rays followed each by a dot. The lower vertical dot is followed by a small triangle. At the left of the upper dot starts a curved line extending downward and to the left to the left-hand dot, thence forming an angle in a curve to the left and down; then joins a horizontal line extending to the left and terminating in a double scroll. This horizontal line is broken by a trefoil. From the lower vertical dot there extends upward a curved line to below the left-hand dot, thence, with an angular joining, extends in a curve line followed by a straight line to the left, these lines parallel to those above described. On the right of the figure is a similar ornamentation.

No. 20 consists of a horizontal scroll ornamented by a tendril, and united to a vertical scroll by a leaf-like ornamentation. Between the two scrolls extends downward and to the left an ornament composed of a bifid figure followed by three dots.

No. 21 is the reverse of No. 20.

No. 19 consists of a shaded band inclined from right to left upward, and terminated by a central curve with tendril-like terminations at right and left. Inside the point of the central curve is a dot. From the base of the right scroll extends to the right a horizontal line, curved at its extremity, and ornamented above by a small tendril. From the base of the left scroll extends downward a vertical line, curved at its extremity, and ornamented on the left by a small tendril.

No. 36. The center is an anthemion in a shaded space, above which is a curved line following the general outline of the figure, terminating at its extremity (right and left) in the bud and scroll ornament. From below the anthemion, beginning with the upper line of the scroll of the anthemion, extends to the left an inclined line, ending in hook terminations, facing the anthemion. The lower lines of the scroll extend upward and to the left, with curved terminations turning downward. In the center of this is a four-pointed star, from the left of which extends a horizontal line crossing the curve and terminating in a dot, to the left of which is a bifid figure terminating in a dot. A similar ornament occurs upon the right of the figure extending to the right. Between the hook terminations and the ring upon each side of the central figure is a bifid figure succeeded by a trapezoidal figure.

No. 30. Upon the left of the figure a scroll, from which, upon the left, proceeds a horizontal line terminating in a dot, and from the curved termination of the scroll upon the right proceeds the horizontal line terminating in a dot, and from the curved portion of the scroll a horizontal line curved to the left at its upper termination, and terminating in a dot.

No. 31. The reverse of No. 30.

No. 22. The figure is composed of two scrolls, each ornamented below by a leaf-shaped figure, formed by deflections of the scroll-line. The scrolls are united angularly below, and the angle of connection is ornamented by a rhomboidal figure. The scrolls are joined above by a broken line, forming a three-pointed figure, below the center of which is a dagger-like ornament.

No. 28. The center of the figure is composed of a trapezoidal figure, on each side of which is a curved triangular figure. Below these triangular figures is a ring, shaded in the upper part of the circumference. To the left of the figure thus described is a scroll ornamented above by a curved leaf-like appendage, and below by a curved line. The right extremity of the scroll-line is united by a horizontal line to the right curve of the scroll on the left. An ornament the reverse of that just described is formed upon the right side of the figure.

No. 39. The center of the figure is an arch composed of small triangles united at their bases. The right and left triangles are more elongated than the others, and are extended, the one on the left in a horizontal line to the left, then extending upward, forming two scrolls, the larger one of which faces the arch, the smaller one from the arch. The large scroll is ornamented by a curved line, which extends toward the arch and then terminates in a scroll. Below the curved line are placed the three triangular figures as ornaments. Above the arch, on the right of the figure, is a zigzag line, forming a series of points parallel to the triangles. Each point is succeeded by a dot. Below the arch is a semicircular shaded figure with five ovoid spaces, ornamented by a series of short curved lines and dots. Below these is a figure composed of two parallel curved lines, joined so as to form rounded extremities. Below these are two horizontal lines, each terminating below the center of the figure in a tendril-like extremity, and on the outside by a curved line connecting it to the semicircular outline of the figure. A figure the reverse of that just described is formed upon the left of the center.

No. 25. Two parallel horizontal lines terminating upon the right in the scrolls, and connected upon the left by a vertical line. From a dot upon the left of the vertical line proceeds the horizontal line, with spear-like termination; and to the left of the spear-like termination upon each side of the horizontal line (above and below) are the curved lines, the forward ends of which are shaded.

No. 34. A horizontal line terminated upon the left in a scroll, from which proceeds a horizontal line having the curved terminations, one above and the other below; the horizontal line crossed by a vertical line, from which on the right extends the curved inclined line joining the end of the upper horizontal line upon the right, the vertical line crossed below the first horizontal by a second horizontal line, connected on the left to the base of the vertical line by a curved inclined line, and terminating on the right in the spear-like ornament, followed by a dot.

No. 35. The reverse of No. 34.

No. 29. An upper and a lower curved line with scroll terminations upon the left, the two connected upon the right by an inclined line; this inclined connecting line crossed by a horizontal line following a dot, and terminated upon the left by the spear-like ornament, followed by a short horizontal line.

No. 44. At the right a bifid figure, from the angle of which to the left extends a curved line ending in a transverse line, then a husk, from which extends to the left a scroll, to the right a curved line, which divides, forming curves to the right and to the left, each terminated by a rhomboidal figure, the three angles of which are button-like in form. In the center of each of these rhomboidal figures is a shaded curvilinear rhomboid. In the space between the curves is a curvilinear triangle. The curves are connected by a zigzag line composed of two short straight and curved lines. From the curved line extends downward and to the right three lines, two curved, each terminating in a tendril, and one straight, the lower extremity of which terminates in a rhomboidal figure similar to those previously described. From the connecting-triangle extends on each side of the tendrils a series of dots.

No. 45. The reverse of No. 44.

No. 42. On the right a scroll ornamented by a tendril, the scroll-line extending to the left as a horizontal line, where it is angularly joined to a curved line which extends downward and to the right, terminating in a half-anthemion, from the upper part of which extends to the left a horizontal line crossing the vertical curve and terminating in a scroll. Below and to the left extends from the anthemion a curved line, which forms, first, a leaf-like curve, then extends downward and to the right, terminating in a section of an anthemion, the lower part of which is bounded by a compound curve forming two scrolls, the upper and left hand one being ornamented by a curved line extending upward and terminating in a scroll.

No. 43. The reverse of No. 42.

No. 37. A scroll terminating upon the right in the ring. From the base of the scroll proceeds the inclined line with the curved terminations. From the center of the scroll extends upward the inclined line, continued to form the oblong figure upon the left, then extends horizontally to the right, and is connected by an inclined line to a second parallel inclined line upon its right.

No. 38. The reverse of No. 37.

No. 33. The upper section of the figure is composed of a ring inclosing a dot. About the ring is a circle of dots. From the ring extends a pendant, the upper line of which is horizontal, with a small bar extending upward from the center. From each end of this horizontal line extends downward a scroll facing outward, and from each of them a scroll facing inward. The space between these last is ornamented by a slender curvilinear rhomboid. Below the rhomboid is a pendant, the lower part of which is a heart-shaped figure inclosing an anthemion. This heart-shaped pendant is suspended by a bifid figure with rounded corners, the body of the figure terminating in a circular extremity inclosing a heavy ring.

No. 48. On the left a trifoliate leaf inclosing a dot, the lower leaf having extended from it to the right and downward a curved line ornamented by a tendril and extending upward, and terminating in a broad circular curve adorned by a tendril-like ornament, and then loops. In the circular space thus formed is a figure consisting of a dot, from which proceed eight rays, four slender and rounded and four with trefoil extremity, these alternating. To the right of the upper leaf of the trefoil is the tendril-like ornament similar to that below the trefoil. To the right of the trefoil is a curvilinear triangle, shaded by horizontal lines. The lower part of the figure is similarly ornamented and placed vertically rather than horizontally. Between these two figures is a figure the general outline of which is that of an anthemion, each leaf being angular, then pointed; below this an elliptical ring inclosing a shaded ellipse; below this a stalk extending to the left and downward, and passing through an ellipse-shaped center, ending in a three-pointed leaf-like expansion.

No. 46. A pendant composed of a scroll terminating to the right, crossed horizontally by the spear-like figure. From the lower portion of the scroll are the leaf and flower-like ornaments.

No. 47. Reverse of No. 46.

No. 41. The center of the figure is a curved rhomboid, the upper lines of which curve and extend above, then bend downward, and terminate in a curved extremity bearing bud-shaded leaves. Between the leaves extend toward the center of the figure a line shaded on the lower side and near the leaves. In the center of the rhomboid is an eight-pointed star with hollow center. Each of the lower oblique rays extends beyond the rhomboid, and terminate in two scrolls. The space between the scrolls is ornamented by a series of dots. From the upper scrolls extend curved lines, which cross the others, and are united above by a dot.

No. 40. The center of the figure is a pendant consisting of a rhomboid and lance-head, ornamented by line and scroll on each side; also outside of the scroll a curved line broken by a ring, and terminating in a dot on each side. Outside of this a half-anthemion much curved, terminating in slender tendrils below and above in the scroll ornamented by leaf-like deflections of the scroll-line and a small curvilinear triangle.

No. 49. A dot succeeded by a curved line ending in a scroll on the right, ornamented by a shaded leaf on the left.

No. 50. The reverse of No. 49.

No. 51. The lower part a square placed diagonally and crossed by a quarterfoil, the ends of which project beyond the square. On the right and left of the square are three leaves, one straight, two broken; above the square a spear-head, with a tendril on each side.

No. 52. A ring inclosing a hollow six-pointed star on each side, and below the ring is a trapzoidal figure.

No. 53. A ring inclosing a shaded circle, in which is a quarterfoil placed upon a vertical line, terminating above in a dot and below in the arrow-heads. On the left of the figure is the inclined line terminating at its base in the arrow-point.

No. 54. The reverse of No. 53.

No. 55. The central part of the figure is an arch formed of small curvilinear triangles, apices downward; between these a series of rings; below the curved ring an arrow-head; above, a trapzoidal figure; to the left of this a curved line parallel to the trapzoidal figure, succeeded by a curved line parallel to the arch, succeeded by a short horizontal line, which at the left turns, forming a three-leaved figure, and returns to the right as a horizontal line parallel to the one above. From the leaf-like extremity proceeds upward a curved line, which enlarges at its extremity, and supports three curves, one leaf-like at its extremity, the other flower-like, the third fruit-like. A similar ornamentation, reversed, occurs upon the right.

No. 56. The same as No. 53, save that the vertical line terminates above in the feather form, and below abruptly.

No. 57. The reverse of No. 56.

No. 58. A ring from which proceed upward three spear-points. Below the ring is a semi-circular series of fine dots. Upon the right and left of the ring extend outward horizontal lines terminating in rings, with leaf-like ornamentation near the rings. From the inner extremities of the horizontal lines extend upward short vertical lines, from the extremities of which proceed scrolls facing the spear-points.

No. 59. A ring inclosing a dot, from which extends on the left an oblique line, forming a loop; then extends horizontally to the left, forms an angle; extends upward and parallel to the oblique line and forms a second loop; extends to the right horizontally, crossing the oblique line on the right; terminates in an elliptical ring, followed by a curvilinear triangle, the apex of which ends in a dot.

No. 60. The reverse of No. 59.

No. 61. The center of the figure is a shaded ring, from which extend three pendants—two simple curves, the third and central one of trapezoidal form. On the left, beginning with a ring surrounding a dot, is a horizontal line, curving downward at the right, and then to the left, forming a scroll, the curved line of which is heavily shaded, and from which extends to the left a half-lance-shaped shaded figure in a horizontal direction. The ornament upon the right is the reverse of that just described.

No. 62. A vertical line terminating above in a cross-like ornament, and below in a dot, a leaf, and a spear-like form. Crossing this line is a scroll, beginning on the right in a leaf-form, ornamented at the left by a leaf-like deflection of the line, and from the central curve of which scroll proceeds a shaded leaf-form and a shaded tendril downward to the right. From the lower line of the scroll proceeds downward and to the right a curved line, crossing the vertical line and terminating in a scroll facing the spear-point.

No. 63. The reverse of No. 62.

No. 64. On the right a scroll ornamented by a scroll. From the lower line of the scroll, extending upward and to the left, is a short line, then upward and to the right, then downward vertically, ending in two horizontal curves. The lower line of the scroll extends to the left as a horizontal line, crosses the vertical line, and then curves upward, turns, retraces its general direction parallel to the first line, and to the left curves, retraces its direction, and ends as a horizontal line with tendril-like ornamented extremity. The curved lines described form a cornucopia, shaded by cross-lines and ornamented by a series of dots which extend from the center of the opening.

No. 65. The reverse of No. 64.

No. 66. The general outline of the center of the figure is a rhomboid, the right and left angles ending in a narrow elliptical ring, from which extend three rays and two scrolls ornamented by a tendril. The rhomboid lines have outside of them lines parallel to them, which lines are deflected upward and across the rhomboid lines, forming in the angles (right and left) a triangle with shaded center. The lower lines of the rhomboid terminate near the lower vertical angle in the spear and tendril point, its upper lines in the simple triangular form. Between them are the three rays, the five points making the crown-like appearance. The central figure of the rhomboid consists of the shaded circular groundwork, in the center of which is a dot inclosed in a ring, from which extend the eight rays terminating in the periphery of the shaded circular groundwork.

No. 67. The center of the figure is an anthemion, the boundary-lines of which extend above and inclose it, then curve, and, in connection with a crown-like ornament between the upper scrolls, form a sort of coronet. To the right and left of the central figure are the scrolls and tendrils. The lower part of the figure is composed of two curvilinear angles, which, in connection with the anthemion boundaries, inclose the rhomboidal spaces, the right and left of which are shaded by vertical lines.

No. 68. From the upper right-hand elliptical ring extends downward and to the left a scroll ornamented by a tendril upon the left and one on the right. From the central leaf-like dot of the scroll extends downward a line terminating in a scroll, and with a leaf-like ornament upon the right. From the elliptical ring extends nearly horizontally to the left a scroll facing upward. These two main scrolls are connected by curved lines, the outer one of which has extending from it five rays, which have concaved extremities.

No. 69. The reverse of No. 68.

No. 70. The center of the figure consists of an elliptical ring surrounded by the four dots, and placed between the oblique lines connected by the trefoil ornament above the ring.

No. 71. The reverse of No. 70.

No. 72. A fret, the lower portion of which is an oblique line terminating in a dot upon the right, and adorned by a scroll followed by leaf-like ornaments placed above the short oblique line terminating in a dot. The left lines of the fret are oblique, the outer one connected by a loop to the upper horizontal line. The second horizontal line terminates in a scroll upon the right.

No. 73. The reverse of No. 72.

No. 74. Upon the right a ring, followed by a concaved square placed obliquely; this followed by an oblique line, broken centrally to form the loop, and terminating upon the left in a transverse rhomboid followed by a leaf, and this by a convex figure followed by a dot. From the convex figure, about centrally, proceeds the scroll. From the right extremity of the figure proceeds a curved line, from which proceed the tendrils.

No. 75. The reverse of No. 74.

No. 76. A ring from which proceeds upon the left a scroll, below which extends to the left a spear-like figure.

No. 77. The reverse of No. 76.

No. 78. An acute-angled fret, the upper line of which is horizontal, the center line zigzag, forming acute angles, and terminated in a tendril upon the right, the right-hand line concaved, and the lower line oblique, cleft, and shaded upon the left.

No. 79. The reverse of No. 78.

No. 80. An oblique line terminated on the left by the tendrils; upon the right shaded below triangularly and terminating in a dot; above the shaded portion a compressed scroll with loop upon the right, followed by a line inclined downward and ending in a tendril. The space between the scroll and the inclined line is ornamented by a shaded line.

No. 81. The reverse of No. 80.

No. 82. An oblique line terminated on the left by a dot, and on the right by a dot, a shaded elliptical ring, and a dot. From the right extends a concaved curve followed by the scroll. Between this scroll and the oblique line is placed a spear-like figure, upon each side of which are the short curved lines terminating in dots, followed by a curved line terminating in a dot, from which proceeds the curved line terminating in a scroll, the lower portion of which scroll crosses the first oblique line.

No. 83. The reverse of No. 82.

Nos. 84 and 85 are dovetailed lines.

Having now set forth my invention, what I claim as new is—

The design for a font of printing-types, substantially as shown and described.

RICHARD SMITH.

In presence of—

GEO. WM. WITHAM,
G. LAW MORLEY.